(57) **CLAIM**

The ornamental design for an instrument panel, as shown and described.

DESCRIPTION

FIG. 1 is a front right perspective view of an instrument panel showing my new design;

FIG. 2 is a front left perspective view of the design shown in FIG. 1;

FIG. 3 is a rear left perspective view of the design shown in FIG. 1;

FIG. 4 is a rear right perspective view of the design shown in FIG. 1;

FIG. 5 is a front view of the design shown in FIG. 1;

FIG. 6 is a rear view of the design shown in FIG. 1;

FIG. 7 is a left side view of the design shown in FIG. 1;

FIG. 8 is a right side view of the design shown in FIG. 1;

FIG. 9 is a top view of the design shown in FIG. 1; and,

FIG. 10 is a bottom view of the design shown in FIG. 1.

The broken lines shown in the figures are included for the purpose of illustrating portions of the instrument panel and form no part of the claimed design.

1 Claim, 10 Drawing Sheets
